Assistant Examiner — Jae Liang

(74) Attorney, Agent, or Firm — Knobbe Martens Olson
& Bear, LLP(57) **CLAIM**

The ornamental design for a beverage container housing, as shown and described.

DESCRIPTION

FIG. 1 is a top side perspective view of a beverage container housing showing my new design;

FIG. 2 is a top perspective view thereof;

FIG. 3 is a bottom perspective view thereof;

FIG. 4 is a top view thereof;

FIG. 5 is a bottom view thereof;

FIG. 6 is an exploded perspective view thereof;

FIG. 7 is a side view thereof; and,

FIG. 8 is an exploded side view thereof.

The broken lines in the drawings depict environmental subject matter of the beverage container housing that forms no part of the claimed design.

1 Claim, 5 Drawing Sheets
